UNITED STATES PATENT OFFICE.

MAXIMILLIAN J. NOWACZYK, OF GRAND RAPIDS, MICHIGAN.

REFRIGERATOR-COUNTER.

1,235,919.

Specification of Letters Patent. Patented Aug. 7, 1917.

Application filed April 19, 1915. Serial No. 22,483.

To all whom it may concern:

Be it known that I, MAXIMILLIAN J. NOWACZYK, a citizen of the United States, residing at Grand Rapids, in the county of 5 Kent and State of Michigan, have invented certain new and useful Improvements in Refrigerator-Counters, of which the following is a specification.

My invention relates to improvements in 10 appliances for cooling and keeping cool vegetables, meats, &c., in stores, meatmarkets and similar places, and its objects are: first, to provide a means whereby an even, consistent temperature may be produced 15 and retained in large storage spaces, as on long counters or show cases; second, to secure perfect drainage in cooling appliances of unusual length, and, third, to provide a means whereby the parts may be readily 20 removed and renovated as desired.

I attain these objects by the arrangement 25 of parts illustrated in the accompanying drawing in which Figure 1 is a longitudinal sectional elevation of a counter and my cooler in position thereon; Fig. 2 is a transverse section of my appliance on the line 30 x, x , of Fig. 1; Fig. 3 is a detached sectional view of a part of the draining appliances; Fig. 4 is a transverse section of the same; Fig. 5 is a plan of one of the draining grates.

Similar letters refer to similar parts throughout the several views.

In the accompanying drawing A represents the cooler case which may be inclosed with glass panels, as indicated at a, a in Figs. 1 and 2. B, B are the storage chambers for the material to be cooled, and C is the ice box chamber. At each side of this 40 chamber, and between it and the chambers B, B I place a partition J which is, preferably, made open in spaces as indicated at j, j so as to insure a perfect circulation of the cooled air from the ice box into the 45 storage chambers. In the ice box I place a water tight bottom E which has downwardly turned flanges e, e at the ends, and above this bottom I place a grate D, provided with open spaces d, d for the free 50 passage of water as the ice melts. The storage chambers B, B are also provided with like grates, as shown in Fig. 1, but the floors of these chambers consist of shallow pans, F, F, formed with high side walls and 55 an out turning flange f' that rests on the flanges g, g of the subfloor G; and with low

walls, f , at one end so arranged that when these pans have been properly placed in the chambers B, B the floor D may be placed in position with its flanges e, e 60 passing inside the pans and engaging with the walls f, f of the pans F, F, to form a passage for water that will positively preclude the possibility of any water leaking from the floor D directly onto the sub-floor 65 G. The other, or outer ends of the pans, F, F are, also provided with the low walls f' designed to hold a small quantity of icy water in the pans before it can flow off onto the subfloor G, for the purpose of 70 utilizing the influence of the cold water immediately after it has passed from the melting ice, as long as possible upon the contents of the chambers B, B, especially in extremely warm weather. By this means the 75 cold water that drips from the ice will naturally settle to the bottom as it moves toward the discharge ends of the pans, so that only the warmer water will drip out of the pans, thus keeping the water in the pans 80 very close to the freezing point. This absolutely prevents any warm air from rising to contact with the bottoms of the vegetable or provision chambers, and greatly economizes the ice consumption. For cool weather 85 use small openings b, b may be made at the bottom of the pans so any water that may drip from the ice chamber into these pans may flow out immediately without any accumulation of water in the pans. 90

The sub-floor G, G, is provided with upwardly extending side and end walls, and outwardly extending flanges g, g arranged to engage and rest upon the rails H, H of the case to support the floors, and with upwardly extending flanges or rims g' , designed to prevent any foul matter from the contents of the chambers B, B from escaping from the grates D, D to the outer surfaces of the case or onto the counter L that supports the case A. The bottoms of the pans F, F incline downward from their inner ends, as indicated in Fig. 1, so that water dripping into the inner ends of the pans will flow toward the low end walls f' 100 until it reaches the top of said walls when the depth of water in the pans will be as indicated by the dotted lines extending from the tops of said end walls to the inner end of the pans, in said Fig. 1. The sub-floor 105 G, G inclines downward from the outer ends at H, H to the center of the case so that

water dripping from the pans F, F onto the sub-floors will flow toward and out of the drain pipe K, in the direction of the arrows in Fig. 1, thus always keeping the pans and floors well drained at all times, no matter how fast the ice in the chamber C may be melting. I, in Fig. 2, represents a cake of ice in the ice chamber C, looking to the left from the dotted lines x, x, Fig. 1 being 10 in section on the dotted lines y, y of Fig. 2.

To remove the parts D, E, and F, it is only necessary to remove the grates D, then the pan E, when the pans F may be readily slid endwise toward the outer ends of the 15 provision chambers and raised out of the chambers when it will be an easy matter to thoroughly clean the pan G and keep the refrigerator well renovated at all times.

The drain pipe K stops just at the upper 20 line of the funnel k, and the trap K' is designed to cut off any possibility of sewer gas entering the space below the refrigerator case A. The pipe K is left open above the funnel k for the purpose of allowing the 25 cold air that accumulates in the space between the pans F, F, and the floor G to pass down and out, thus preventing the accumulation of foul air in the refrigerator, the flow or dripping of water through the 30 pipe K being so small that it will not only not obstruct the passage of air therethrough, but will facilitate it.

It will be readily understood from the foregoing description and the accompanying 35 drawing that the air circulation in this refrigerator must be directly from the chamber C in opposite directions over the contents of the chambers B, B and then around the ends of the pans F, F into the space between the pans F, F and the floor G and 40 out of the pipe K, insuring a perfect circulation of pure cold air at all times from the ice box through the provision chambers, thus rendering it possible to store smoked meats 45 or other strong odored substances in one end of the refrigerator, and the most delicate viands in the other end without danger of either becoming tainted from the other.

The arrows shown in the chambers B, B 50 and C and in the flue between the pans F, F and the floor G, G, indicate the air circulation from the ice chamber C through the provision chambers B, B into the flue between the pans F, F and the floor G, whence it escapes through the pipe K and 55 out over the funnel k, as hereinbefore stated.

What I claim as new, and desire to secure by Letters Patent of the United States, is:

1. A counter refrigerator having a cen-

tral ice chamber and a provision chamber 60 at each side thereof; in combination with a cold water retaining pan below each provision chamber, the outer ends of said water pans being a little lower than the side walls and the other end walls, and set to 65 form a narrow space between the ends of the pans and the ends of the case, a water tight floor under the ice chamber, said floor having downwardly extending flanges in position to carry the drip of water from the 70 ice chamber into the cold water retaining pans, a closed floor below the water pans, said floor and pans forming an air tight floor below the ice chamber and the provision chambers except at the ends of the case, 75 said closed floor inclining downward toward the center of the refrigerator case, and a drainage pipe connected therewith.

2. In a counter refrigerator, a central ice chamber, a provision chamber at each end 80 of the ice chamber, a water tight floor below the ice chamber, a water pan extending from each end of the ice chamber floor to a position near each end of the refrigerator case forming a water and air tight floor 85 below the ice chamber and the provision chambers except at the extreme outer ends of the pans, a water tight floor below the water pans forming an incline downward from each end toward the center of the 90 case, and a drain pipe connected therewith, all arranged to cause a current of cold air to pass from the ice chamber through each provision chamber and downward past the 95 ends of the water pans and along the surface of the inclined floor to and out of the drain pipe.

3. A refrigerator having a provision chamber at each end and an ice chamber between the provision chambers, means for 100 air circulation from the ice chamber through both provision chambers, cold water containing pans located under the provision chambers, a water tight floor under the ice chamber, means for causing all water from 105 melting ice to flow into the water pans, said pans so arranged that water can flow out over their outer ends only, a floor below the pans inclining from each outer end downward toward the center, the ice chamber 110 floor and the water pans forming a water tight partition between the chambers, and said inclined floor, except at the outer ends of the pans, and a drain pipe connected with the floor.

Signed at Grand Rapids Michigan April 15, 1915.

MAXIMILLIAN J. NOWACZYK.
